ATTORNEY.

UNITED STATES PATENT OFFICE.

HENRY H. STEIN, OF FORT WAYNE, INDIANA.

TOWEL SUPPORT.

Application filed April 7, 1927. Serial No. 181,876

The invention relates to supports for towels and its object is to provide means by which a towel or other similar article may be continuously supported on a wall or other structure and capable of movement in a plurality of directions, the device automatically retracting the towel to normal position when released.

The invention is illustrated in the accompanying drawings, in which

Figure 1 is a front elevational view of a device embodying the invention; Fig. 2 a side elevational view of the same; Fig. 3 a plan view of the same installed in a wall and Fig. 4 a vertical longitudinal cross-section of the device.

In the illustrative embodiment of the invention, 1 represents the wall of a building or other structure, 2 is a U-shaped frame or bracket secured to or projecting from a plate 3 adapted to cover an opening 4 in the wall through which the frame is extended. A pulley 5 is mounted at the rear or inner end of the frame over which runs a cord or cable 6 having a counter-weight 7 secured to one end thereof. The other end of the cord or cable extends through an aperture 8 formed in the plate 3, an eyelet 9 being mounted in the aperture to provide a smooth surface on which the cord or cable may move. A clamp 10 of suitable form is secured to the outer end of the cord or cable. This clamp is adapted to be engaged to the towel or other article 11 for supporting it. The rear end of the clamp, or the looped end of the cord or cable at the clamp, will abut the plate at the aperture 8 in the plate 3 and limit the inward movement of the cord or cable.

A brake member 12 of suitable material is loosely mounted on a pin 13 that is mounted on the frame, preferably rearwardly of the pulley 5. The face 14 of the brake that opposes the pulley preferably forms a cam adapted to engage the cord or cable and clamp it to the pulley when the brake is rocked. A spring 14^a is engaged at one end to the frame 2 and its opposite end is engaged on a pin 15 that projects from the upper portion of the brake member. A rod

16 loosely engages the lower end of the member 12 and is extended through a slot 17 in the plate 3. A finger grip 18 is attached to the outer end of the rod and the slot 17 is wide enough at its upper end to permit the grip to pass into it, the lower portion of the slot being narrowed so that while it will receive the rod 16 the grip 18 will abut the outer face of the plate about the slot 17. By pulling outwardly on the rod 16 the member 12 is rocked on its pivot to cause its cam face to move away from the cord or cable as shown in full lines in Fig. 4, and by moving the rod into the restricted portion of the slot the brake member, opposed by the spring 14, is held in normal released position. When the cord or cable is pulled out to use the article attached to the clamp, and it is desired to retain the article in its new position, the rod 16 is elevated to cause the grip to register with the wider or expanded portion of the slot 17, as shown in Fig. 2 and in broken lines in Fig. 4, whereupon the spring 14 expands and rocks the brake into contact with the cord or cable and firmly clamps the same on the pulley so that the weight will not descend.

What I claim is:

A support for towels and the like comprising a plate adapted to be secured over an opening in a wall and having an aperture therein, a frame extending rearwardly from the plate and adapted to be inserted through the opening in the wall, a pulley revolvably mounted adjacent to the free end of the frame, a cable passed over the pulley and extended forwardly through the aperture in the plate, a clamp secured to the forward end of the cable, a weight secured to the opposite end of the cable, a brake member pivotally mounted on the frame and adapted to clamp the cable to the pulley, a rod pivotally connected to the brake member and extended through the plate and adapted to rock the brake member, and tension means opposing said rocking movement.

In witness whereof I have hereunto signed my name this 5th day of April, 1927.

HENRY H. STEIN.
